UNITED STATES PATENT OFFICE

FREDERICK M. MINER, JR., AND WALTER C. DAUMLING, OF MADISON, WISCONSIN

BOILER

Application filed July 8, 1929. Serial No. 376,543.

The invention relates to gas- or oil-fired boilers of the flue tube type.

The object of the invention is to provide a boiler of the type described in which the burner discharges the burning gases directly into the inlet end of the flue tube which is surrounded by a lateral extension of the boiler and in which the flue tube structure preferably includes a plurality of coiled 10 pipes joined to flue tube headers that are detachably connected to the inlet and outlet sections of the flue tube to permit ready inspection and repair, the boiler being made in sections to permit access to said removable flue 15 tube section, the arrangement providing a very simple, reliable and efficient boiler construction.

The invention further consists in the several features hereinafter described and more 20 particularly defined by the claim at the conclusion hereof.

In the drawings Fig. 1 is a side elevation view of a boiler embodying the invention;

Fig. 2 is a detail sectional view taken on 25 the line 2—2 of Fig. 1;

Fig. 3 is a detail sectional view through the removable flue tube section.

Referring to the drawings, the numerals 4 and 5 designate the sections forming the 30 main casing of the boiler, said sections having flanges 6 detachably secured together by bolts 7 with a packing ring 8 disposed therebetween. These casing sections are of cylindrical section except that a laterally-disposed, semi-cylindrical extension 9 is provided on the casing section 5.

A cold water inlet pipe 10 enters the lower 40 end of the section 5 and a hot water or steam pipe 11 leads from the top of the section 4 and the casing is preferably supported above the floor 12 by legs 13.

The flue tube structure is disposed in the section 5 and comprises fixed inlet and outlet flue tube sections 14 and 15 and a removable 45 flue tube section 16.

The tube section 14 consists of an angled conduit whose vertical leg 17 extends through the extension 9 and projects beyond the bottom 18 of the same and, as shown, an ordinary gas burner is associated with the ex-

posed lower end 19 of said sections to deliver burning gases thereto. This burner includes the gas supply pipe 20 leading into a Venturi mixing tube 21 having the burner tip 22 at its upper end and primary air openings 23 at its lower end, said tip 22 projecting up into the end 19 and spaced from the walls thereof to allow passage of the proportioning air that enters through the side openings 24 formed in the supporting spider 25 of the burner. It will, of course, be understood that instead of using gas as a fuel, oil may be used, supplied by any suitable oil burner associated with the end 19.

The tube section 15 is shown as a straight pipe section that extends through the casing section 5 adjacent the lower end portion thereof and is connected by a union coupling 26 with a pipe 27 leading to the chimney.

The horizontal leg 28 of the tube section 14 has an annular flange 29 at its end and the inner end of the tube section 15 is provided with an annular flange 30.

The removable tube section 16 includes 75 headers 31 and 32 and a plurality of coiled pipes 33 connecting these headers together and secured thereto in a fluid-tight manner.

The header 31 has an annular flange 34 detachably secured by bolts 35 and packing 36 to the flange 29 and the header 32 has an annular flange 37 detachably secured by bolts 38 and packing 39 to the flange 30 so that with the top section 4 removed it is an easy matter to remove the tube section 16 from the boiler if repair or cleaning is necessary.

The tube sections 14 and 15 and headers 31 and 32 may be of suitable iron or steel piping, but the pipes 33 are preferably of metal having a high rate of heat-conductivity, such as copper or copper alloy.

A drain pipe 40 for the condensate extends from the tube section 15 to a suitable place of disposal and has a trap 41 formed therein.

With this construction the hot burning gases enter the tube section 14 and pass upwardly through the same and then laterally into the header 31 and pipes 33 to the header 32 and tube section 15 and it has been found that by the time these gases have passed through or partially through the pipes 33 all 10c

the heat has been given up to the flue tubes and the water surrounding the same so that the gases in the tube section 15 are at the temperature of the entering water, with the result that the water or sulphuric acid in the gas is condensed and flows out through the pipe 40 so that damage to the chimney and fumes from the gas are prevented. It has also been found that as practically all the heat of the gases is given up to the water the heater is very efficient.

We desire it to be understood that this invention is not to be limited to any particular form or arrangement of parts except insofar as such limitations are included in the claim.

What we claim as our invention is:

In a boiler, the combination of a vertically disposed cylindrical casing, having a removable top portion, a flue tube structure comprising an inlet tube section extending upwardly and then horizontally, an exhaust tube section disposed below the horizontally extending portion of said inlet tube section, an intermediate tube section including headers detachably connected to said tube sections and coiled pipes connecting said headers, said last named tube section being readily removable through the upper end of said casing on the removal of said top portion, a trap for condensation products communicating with said exhaust tube section at a low point in the latter, said tube structure being of a length to insure complete combustion of the burning gases before reaching that portion of the exhaust section adjacent said trap, an inlet for the supply water entering said casing below and adjacent said exhaust tube section to insure the cooling of the burnt gases so that the water or sulphuric acid in the burnt gases is condensed and flows out through said trap so that damage to the piping beyond said trap is prevented, and a burner for delivering burning gases to the inlet end of said inlet tube section.

In testimony whereof, we affix our signatures.

FREDERICK M. MINER, JR.
WALTER C. DAUMLING.
